UNITED STATES PATENT OFFICE

JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY

TABULATING MACHINE FOR OPERATING IN FRACTIONS

Application filed September 28, 1927. Serial No. 222,463.

The invention concerns accounting machines and has for its principal object the provision of mechanism for adapting a machine operating according to one system of mathematical progression to another system and to furthermore provide simple and novel mechanism for this purpose necessitating fewer and less radical changes in the control and data receiving devices than have heretofore been required.

An equally important object of the invention is to provide such mechanism of universal application capable of adapting each data receiving unit to a single denominational order regardless of whether the increment of progression is greater or less than that for which the controls and receiving devices are normally designed. For example the usual accounting machine normally operates according to a decimal system and may be modified to operate according to fractions in certain orders provided the fractional denominators are less than ten. If it is desired to operate in certain orders according to fractions whose denominators are greater than ten various expediencies have been resorted to, such as using several entering units for the single fractional order. It is often very convenient to adapt one denominational order to twelve for handling the English monetary system or inches and feet and owing to the importance of this fraction in accounting machine practice it will be selected to illustrate the method of practicing the invention.

Another object of the invention is to provide mechanism for adapting an accounting machine normally operating according to a decimal system to operate according to fractions in certain orders without introducing lost motion connections.

Another object of the invention is to provide mechanism for record controlled accounting machines to permit record cards having normally spaced index point positions to control machine operation in such manner as they would if the index point positions were spaced closer together on the cards, that is to substantially contract the index point spacing with respect to machine operation.

A well known type of printing tabulator is

controlled by cards having ten index point positions equally spaced from each other in each card column. The corresponding printing type have the same spacing on a type bar and the type bar and card are moved synchronously so that as the index point positions move successively past the record analyzing mechanism the corresponding type on the bar pass through printing position. When the analyzing mechanism encounters an index point it controls devices for arresting the motion of the type bar bearing the type corresponding to the index point in printing position. Now if instead of ten index point positions the card is provided with twelve spaced as before and the type bar is provided with twelve type spaced closer together on the bar so that they pass through printing position in the same time as the ten formerly did, it is obvious that the analysis of the card and the movement of the type bar no longer agree. The contracting feature of the invention provides for maintaining synchronous motion between the card feed and the type bar and compensating for the increase in the length of the analyzing operation due to the extra index points.

Another object of the invention is to provide mechanism for record controlled accounting machines to permit record cards having normally spaced index points to control machine operation in such manner as they would if the index points were spaced further apart on the cards, that is to substantially expand the index point spacing with respect to machine operation. This is substantially the reverse of the contracting operation. For example, only eight index point positions might be used on a card column and eight corresponding type located on a type bar covering the same space that ten normally covered. To maintain synchronous motion between the card and type bar in this case the increase of type spacing on the bar must be compensated.

Another object of the invention is to provide for rearrangement of the index points on a controlling record for entry into the accounting mechanism of the machine. The usual single hole control card is provided

with ten entering index point positions arranged in the order 9, 8, 7, 6, 5, 4, 3, 2, 1, 0 and two additional index point positions which follow the 0 for other purposes. If the extra index point positions were used for 10 and 11 in a twelve point system the machine would have to be arranged to transpose the entering order so that the effect on the accounting mechanism would be the same as if the index point positions were arranged on the card in the order 11, 10, 9, 8, 7, 6, 5, 4, 3, 2, 1, 0. This transposition is provided for in the present invention.

Another object of the invention is to provide translating mechanism for effecting the above translations consisting of a reading-in commutator cooperating with the analyzing mechanism to effect setups from which the translated data may be entered into the accounting mechanism.

Another object of the invention is to provide setup mechanism for the above translation consisting of a commutator with brushes shiftable transversely thereof.

Another object of the invention is to provide translating mechanism for the above translation in which each shiftable brush is provided with an individual shifting magnet.

Another object of the invention is to provide translating mechanism for the above translations in which entries are received from a controlling card during one machine cycle and the translated data are entered into the accounting mechanism during a subsequent machine cycle.

The invention will be described, by way of example, in connection with a specific form of record controlled printing tabulator. The tabulator is controlled by record cards on which numerical data may be represented by index points or perforations placed in any one of ten differentially located index point positions in each card column, a single index point in a column representing a particular digit, according to its location. The cards are fed with a continuous motion one each machine cycle, beneath analyzing brushes of which there is one for each card column, so that the brushes search the index point positions successively. The driving mechanism of the adding devices and the driving mechanism of the printing devices operate synchronously with the card feed. A magnet is connected to each analyzing brush for controlling one denominational order of the adding mechanism and an operating pulse through this magnet results in coupling the adding device to its driving mechanism, the coupling persisting until a predetermined point in the machine cycle when it is automatically released. The pulses from the analyzing brush then momentarily energize the magnet in accordance with the location of the index points and effect entry of the digits

represented by their location into the adding mechanism.

The printing mechanism consists of a plurality of type bars, one for each card column, which are moved synchronously with the card feed to present type corresponding to the several index point positions on the card in printing position as the index point positions pass under the analyzing brushes. A control magnet, when energized from a pulse initiated when an analyzing brush encounters a perforation, arrests the motion of the type bar leaving the type corresponding to the digit represented by the location of the perforation on the card in printing position. Both the printing and adding mechanisms are thus controlled by current impulses differentially timed during the machine cycles.

According to what is at present believed to be the preferred form of the invention the contraction, expansion or transposition, as the case may be, is effected through an auxiliary mechanism interposed between the analyzing brush and the adding or printing magnet. As a card is fed beneath the analyzing brushes the current pulses resulting from index points, instead of acting directly upon the adding or printing magnets to enter the data, act upon the intermediate auxiliary mechanism to effect setups corresponding to the locations of the index points on the card. During the following machine cycle after the card is entirely clear of the analyzing mechanism the set up is reconverted into a timed current impulse for operating the adding or printing magnet. The auxiliary mechanism, however, has provisions for retiming the impulses so that they occur in the proper order and with the proper timing to operate the adding and printing mechanism according to the required expansion, contraction or transposition.

The intermediate auxiliary mechanism of which one is provided for each card column, may consist generally of two commutator devices, one of which will hereinafter be referred to as the reading-in commutator and the other as the reading-out commutator. The reading-in commutator rotates synchronously with the card feed and has a series of contacts on its periphery arranged in groups equal in number to the active index point positions on the card. The groups are spaced to engage brushes riding on the commutator surface as the analyzing brush passes the several index point positions on the card and the commutator contacts are electrically connected to the analyzing brush. When the latter encounters a perforation a combination of circuits is closed through the particular group of commutator contacts then under the commutator brushes and these combinations are different for each index point.

The reading-out commutator is rotated synchronously with the driving mechanisms

of the adding and printing devices. In the present case it has been assumed that these mechanisms operate synchronously with the card feed as they ordinarily would in machines of this type but, of course, this is not essential and they might have a different type of movement altogether. The reading-out commutator is provided with a plurality of brushes shiftable transversely of its sur-

10 face, each of which may selectively engage one of two circumferential rows of contacts on the commutator surface. The brushes are shifted by individual magnets connected in the circuits extending through the reading-in 15 commutator brushes and the analyzing brush, from which it will be understood that a certain combination of brushes are shifted for each index point encountered by the analyzing brush. The circumferential rows of contacts on the reading-out commutator are likewise arranged in transverse groups equal in number to the different characters which might be entered into the adding and printing mechanisms. These transverse groups 20 are arranged to complete circuits through the shiftable brushes and the adding and printing magnets at certain times in the machine cycle according to the particular combinations of brushes which have been shifted. Obviously 25 the contact groups may be arranged to initiate impulses timed as desired with respect to the machine cycle and the required expansions, contraction and transpositions are thus provided for.

30 The invention may be most clearly understood from the following detailed description which should be read in connection with the accompanying drawings in which the same reference numerals refer to the same parts throughout the several views and in which:

35 Fig. 1 is a plan view of one complete translating or intermediate mechanism for a denominational order.

40 Fig. 2 is a diagrammatic sketch showing developments of the commutators to illustrate the operation of the device.

45 Fig. 3 is a detail showing the driving connections between the adding units of the machine and the translating units.

50 Fig. 4 is a detail section through the adding section of the machine illustrating the operating of the total taking mechanism.

55 Fig. 5 is a sketch illustrating the contraction of the entering cycle over the analyzing cycle.

Figs. 6 and 7 are detail views of the reading-out commutators showing the parts in different positions.

60 Figs. 8 and 9 are detail views of a normal ten type bar and a twelve type bar aligned for comparison.

65 Fig. 10 is a sketch similar to Fig. 2 but showing the operation of the device as applied to an expanding operation.

66 Fig. 11 is a sketch similar to Fig. 5 illustrating the expansion of the entering cycle over the analyzing cycle.

Figs. 12 and 13 are detail views of the type bars similar to Figs. 8 and 9 but showing a normal ten type bar aligned with an eight type bar for comparison, and

Fig. 14 is a circuit diagram of a complete printing tabulating machine according to the invention.

The invention is shown in Fig. 14 as applied to a well-known type of tabulator fully described in the copending application of Daly and Page, Serial No. 6980, filed February 5, 1925 (now Patent No. 1,762,145, issued June 10, 1930). The tabulator is represented diagrammatically and its circuit diagram and general operation will be explained only in sufficient detail to make the operation of the present invention clear.

The accumulating and printing mechanism together with all other mechanical parts involved in tabulating and listing operations are driven by the tabulating motor TM while the total taking mechanism and the printing devices in total printing operations are driven by the reset motor RM. Before starting a tabulating operation the machine must be driven through a reset cycle to clear the accumulators of any data which might remain in them from a previous tabulating operation and also to prepare the circuits of the tabulating motor for operation. The reset cycle is started by depressing the reset key R closing a circuit through the reset motor RM from one side of the main line 21 through

reset motor RM, reset clutch magnet 22, contacts 23 and normally closed listing contacts L-2 to binding post 12 in the other side of the main line 26. Immediately after starting the cam contacts P-1 close shortcircuiting the reset clutch magnet 22 to permit the reset clutch to disengage at the end of the cycle, and the reset motor itself is stopped at the end of the cycle by the opening of these contacts. This reset cycle momentarily closes

and then opens the lower contacts P-3 thereby energizing motor control relay 84 in series with its stick magnet 91. The stick magnet prepares an additional circuit through cam contacts C-1, closed in the rest position of the tabulating mechanism, to hold the magnet 84 energized. As long as this magnet remains energized its contacts indicated at 86 are closed to prepare the starting circuits of the tabulator motor TM.

After the contacts 86 are closed, the tabulating motor may be started by depressing the start key ST whereupon the starting circuit of the tabulating motor TM is established from the main line 21, through the tabulating motor to binding post 16, thence through the card feed clutch magnet 25 and start key contacts ST, motor relay contacts 86, through stop key contacts S to binding post 9 and through upper contacts P-3 closed except

during reset operations, to binding post 12 in the other side of the line 26. The tabulating motor TM and the card feed clutch magnet 25 remain in operation through their various circuits, which need not be described in detail, as long as the contacts 86 of the motor control relay 84 remain closed.

The card feed clutch magnet 25 when energized causes engagement of the card feed clutch which through suitable picker mechanism indicated at 27 causes the cards 28 in the magazine of the machine to feed one at a time beneath the upper analyzing brushes 30 and the lower analyzing brushes 31, one card feeding beneath the upper brushes during one card cycle and beneath the lower brushes 31 during the following card cycle while the succeeding card is feeding beneath the upper brushes 30. The circuit of the motor control relay magnet 84 when once established includes the cam contacts C-1 in series and these cam contacts open for a brief interval each machine cycle tending to open the circuit and deenergize the magnet 84 to open the contacts 86 and stop the tabulating motor. The contacts C-1 are shunted by the automatic control contacts 35 of the machine, any number of which may be plugged in series to control machine operation. These contacts are normally open but are closed whenever their controlling magnets 36 are energized and when closed remain so until after the contacts C-1 have opened and closed during the machine cycle.

33 The upper brushes 30 cooperate with contact blocks 37 which are connected to sockets 38. The lower brushes 31 through similar contact blocks 39 are connected to sockets 40. It will be understood that although only two 10 upper and two lower brushes are shown in the drawings, the machine may be provided with any number of them to operate on any number of card columns, the usual commercial machine containing 45 upper and 45 lower brushes. Certain of the card columns are chosen for group control data and the group control magnets 36 are connected in series through the sockets 38 and 40 with the corresponding upper and lower brushes. As long as the control perforations in the control columns of the cards under the upper and lower brushes during a card cycle agree, the magnets 36 are energized at some time during the cycle closing their contacts 35 and establishing a shunt about cam contacts C-1. The machine thereupon remains in operation for another card cycle. As soon as the control perforations in the cards under the upper and lower brushes fail to agree, indicating the end 50 of a card group the control magnets 36 fail to energize, control contacts 35 remain open and the opening of cam contacts C-1 during the cycle causes deenergization of the motor relay 84 permitting contacts 86 to open interrupting the normal operating circuit of the

tabulating motor. The contacts 86 are shunted by cam contacts T-1 and L-6 and after the contacts 86 open the tabulating motor circuit is maintained through one or the other of these cam contacts until a certain point in the machine cycle when it is interrupted by them to stop the tabulating motor and the parts driven thereby in normal home position.

70 During card feeding cycles the lower brushes 31 are energized from the main line 26 through a circuit extending from binding post 12, through upper contacts P-3 and binding post 9 to cam contacts L-6 or T-1 thence through wires 41 and 42 to lower card lever contacts LC, closed as long as cards 80 are passing the lower brushes, thence through wire 43 to cam contacts T-2 and T-3 and through wire 44 to the lower brushes 31. The cam contacts T-2 and T-3 open and close to permit energization of the lower 85 brushes only when the data carrying portion of the card is passing the lower brushes. As the cards pass the lower brushes their index perforations permit the lower brushes 31 to instantaneously engage their cooperating 90 contact blocks 39 to continue the brush circuits to the sockets 40 which may be plugged to the usual adding and printing devices of the machine. The left hand brush 39 is shown so plugged to a counter magnet 164 95 for controlling it in the usual manner according to a decimal system. The differentially timed impulses resulting from the index points serve to energize magnet 164 at differential times during the cycle to operate the 100 adding and printing mechanism of the machine in a manner well understood.

105 In the present case the right hand upper brush 30 is shown connected with translating mechanism according to the present invention to read a certain card column for twelfths instead of tenths and to modify the effect of the entering impulses. The reason for using an upper instead of a lower analyzing brush for this purpose will appear later. The general scheme of operation of this translating mechanism will be explained in connection with a system for adding twelfths on certain accumulators and printing elements in a machine operating normally according to the decimal system.

110 Referring to Fig. 5 a controlling card of the Hollerith type is shown at H provided with index point positions in columns for the digits from nine to zero with two extra index point positions after the zero, designated as ten and eleven. The analyzing brushes cover the index point positions in the order 9, 8, 7, 6, 5, etc. A normal type bar 115 of the machine is shown in Fig. 8 and this bar rises synchronously with the passage of the card past the analyzing brushes to bring its type opposite the printing line 45 as the corresponding index point positions on the card 120 are passing the analyzing brushes. If the 125

brush finds a perforation in any position, the resulting impulse operates a printing magnet to arrest the upward motion of the type bar leaving the type corresponding to the index point opposite the printing line to permit printing at a later point in the cycle. The adding mechanism operates in a similar manner except that the impulse results in clutching the counter elements to their driving shaft for a definite time in the cycle corresponding to the index point which causes the impulse. Referring again to Fig. 5, if it is desired to operate the machine in certain columns according to twelfths instead of tenths, the two upper index point positions 10 and 11 may be used but this results in lengthening the analyzing portion of the cycle and also in displacing the 10 and 11 index points from their logical progressive positions on the card; that is, instead of being analyzed prior to the 9 index point position they are analyzed after the zero index point position. In Fig. 9 a type bar 50 is shown with twelve type designated from zero to eleven spaced within the same spacing as the ten type on the normal type bar 48 in Fig. 8, and in order to make the machine standard as far as possible, it is necessary that the type bar 50 move synchronously with the other decimal type bars 48 of the machine. To operate this type bar (see Fig. 5) it is necessary not only to compress the longer analyzing cycle into one of normal length but also to rearrange the order of the index points as indicated at T. If this is done, the printing magnet 51 in Fig. 9 will be operated to trip the latch 52 permitting it to engage the several teeth 53 on the type bar 50 to arrest the type on this bar in the proper position for printing.

The general manner in which this compressing and transposition is effected may be understood from Fig. 14. This right hand upper analyzing brush 30 controls the twelfths printing and counter magnets through intermediate translating mechanism which in the present case consists of a reading-in commutator 55 and two pairs of reading-out commutators 56 and 57. The analyzing brush is connected to a brush 46 making contact with a continuous conducting strip 47 on the reading-in commutator. The reading-in commutator is driven in synchronism with the card feed making only one half a revolution, however, for each card feeding cycle. Two sets of brushes 59 and 60 cooperate with a group of contacts 61 on the commutator surface. The contacts cover substantially half of the periphery and coat with the brushes 59 during one card feeding or machine cycle and with the brushes 60 during the following machine cycle. The brushes 59 control magnets 62 and the contacts 61 are arranged so that a certain group of them is under the brushes 59 when a certain index point is under the ana-

lyzing brush thereby energizing the magnets 62 in different combinations for each index point on the cards. The brushes 60 control similar magnets 63 during alternate cycles in an identical manner. The two pairs of reading-out commutators 56 and 57 are operative during alternate cycles and are provided with shiftable brushes which are shifted under control of the magnets 62 cooperating with the brushes of the commutators 56 and magnets 63 cooperating with brushes of commutators 57. The shiftable brushes cooperate with contacts on the surface of reading-out commutator to retime and rearrange the entering impulses from which the counter magnet 64 is energized at the desired time to enter the data which is recorded on the cards. The data is read from the card during one cycle and the magnets 62 energized to shift the brushes on the commutators 56 and during the following cycle when the succeeding card is under the analyzing brushes the commutators 56 cooperate with the brushes as shifted to energize the counter magnet 64 at the proper time during the cycle. During this following cycle the contacts 61 cooperate with the brushes 60 to energize the magnets 63 for shifting the brushes on the commutators 57 and the data from this card is entered into the counter magnet during the next following cycle.

The operation of contracting and transposing data entries may be best understood from Fig. 2 of the drawings in which the reading-in and reading-out commutators are shown in development. The contacts 61 on the reading-in commutator surface are arranged in four circumferential rows indicated at A, B, C, and D, each row cooperating with an individual brush 59. The contacts 61 are also arranged in transverse rows designated as 9, 8, 7, 6, 5, 4, 3, 2, 1, 0, 10 and 11, each transverse row except the one designated 0 containing one or more contacts. The motion of the commutator is such that the row 9 marked 9 is under the brushes 59 when the 9 index point position on the card is passing the analyzing brush and so on. Whenever the analyzing brush encounters a perforation a certain combination of the magnets 62 is energized to shift corresponding brushes 65 on the reading-out commutators 56.

The reading-out commutators are likewise each provided with four circumferential rows of contacts 66 arranged also in transverse rows designated as 11, 10, 9, 8, 7, etc. Each brush 65 normally cooperates with one circumferential row of contacts 66 but when its magnet 62 is energized is shifted to cooperate with an adjacent row. The upper brush 65 of the upper commutator 56 is connected through a wire 67 to one side of the line, the next lower brush 65 is connected to the upper brush on the lower commutator 56 and the lower brush on this lower com-

mutator is connected by wire 68 to the counter magnet 64 (see also Fig. 14). The entering circuit thus includes two breaks across the two sets of brushes 65. In the normal position of the brushes the passage of the contacts 66 beneath them will not close this circuit. After the brushes have been shifted in accordance with an index point one of the transverse rows of contacts 66 simultaneously bridges the two pairs of brushes at a given point in the cycle resulting in an entering impulse through the counter magnet. The timing and order of this entering impulse depends, of course, on the arrangement of contacts 66 in transverse rows and obviously the order and timing can be arranged in any desired manner. It will be noted that the transverse rows of contacts 66 are spaced closer together than the transverse rows of contacts 61 which accounts for the contracting feature. The arrangement of the contacts in rows provides also for the transposition of the 10, 11 impulses to their proper place in the series.

The operation will be clearer from a specific example. Assume that an index point occurs in the 6 index point position of a card under the upper brush. As this index point encounters the analyzing brush a circuit will be completed through the brush 46 and conducting strip 47 to the contacts 61 in the 6 row, that is in the A and D circumferential rows. Owing to the synchronous movement of the card and commutator, the 6 row is at this time under the brushes 59 and the circuit 35 is extended in two branches, one leading to the magnet 62 designated A and the other leading to the magnet 62 designated D thereby by energizing these magnets to shift their corresponding brushes 65 on the reading-out 40 commutators 56. After the shifting is complete the upper brush 65 cooperates with the second circumferential row on the upper commutator 56 and the lower brush 65 on the lower commutator cooperates with the lower 45 circumferential row of contacts 66 on this commutator. As a 6 is to be entered into the accounting and printing mechanism, indicating in the present case six twelfths, it will be noted that no circuit can be completed through the contacts 66 until the transverse row 6 comes under the shiftable brushes 65. At this time each pair of brushes 65 will be bridged simultaneously by the connected 50 contacts in the row and the resulting operating impulse operates the counter and printing magnets. Other index points on the record card operate in a similar manner to control the shiftable brushes 65 to initiate an 55 entering impulse at the proper time in the following card cycle. It will be understood that the pulses initiated from index points in the right hand column of the card shown in Fig. 5 have thus been rearranged and spaced closer together as indicated by the 60 points 11, 10, 9, 8, 7, 6, 5, etc. designated T.

The effect of this on the adding cycle will be clearer from Fig. 3. In this figure is shown in fragmentary form an accumulating mechanism according to the U. S. patent to Lake No. 1,307,740 filed June 24, 1919. The counter wheels 69 are driven through gear trains 70, one gear of which is freely mounted on the counter shaft 71. The counter shaft rotates during adding cycles but the gear trains 70 do not rotate until they are positively clutched to the shaft. The clutching mechanism comprises clutch teeth on the side of the gear of train 70 which is mounted on the shaft and sleeve members 72 which are splined to the shaft but shiftable in and out of engagement with the clutch teeth on the gear. The clutching engagement is effected by momentary energization of the counter magnet 64. This magnet is provided with a pivoted armature 73 which carries a latch for pivoted lever 74. This lever has one end extending into an annular groove in the clutch sleeve 72 and its other end spring-pressed by one of the spring contacts 75 urging it to clutching position, from which it is normally maintained, however, by the latch on armature structure 73. When the magnet 64 is energized to attract its armature the latch is released permitting the lever 74 under action of the spring contact 75 to force the clutch sleeve 72 into engagement with the teeth on the counter drive gear clutching the latter to the shaft and causing it to rotate therewith until a predetermined point in the cycle when all clutches which are engaged are automatically kicked out simultaneously. The entry on the counter wheel 69 therefore conforms to the differential timing of the impulse which energized magnet 64.

The translator mechanisms indicated generally at 80 of which one is provided for each card column in which a translation is to be made are driven in synchronism with the counter shaft 71 through a gear train 81 having a gear ratio to cause the reading-in and reading-out commutators to make one revolution for each two card cycles or every two revolutions of counter shaft 71. The operating elements of the translators 80 are driven from gears 82 fixed to a shaft 83 which is driven by the gear train 81. It may be assumed that the lower counter wheel 69 is arranged to indicate twelfths while the others are arranged to indicate tenths. The driving connection between the twelfths counter wheel 69 and the shaft 71 is similar to that for driving the other counter wheels in that it comprises a constantly meshed gear train and a similar clutching element. Either the gear train or the gear teeth for this twelfths unit must be arranged so that the counter wheel may rotate in increments of twelfths instead of tenths. The complete driving cycles of all the counter elements coincide, however, and the twelve increments of move- 130

ment of the lower counter wheel may occur within the same elapsed time as the ten increments of movement of the other counter wheels. The different timing of the entering impulses for the twelfths unit are spaced within the normal entering cycle as just explained and as indicated in Fig. 5.

The relation between the normal ten type bar and the twelve type bar used in one order in the present case is illustrated in comparative Figures 8 and 9. In Fig. 8 the normal type bar carrying ten type with normal spacing is provided with nine notches 85 to permit arresting the type bar in any of the nine positions represented by the type one to nine. In Fig. 9 the type bar 50 carries twelve type from zero to eleven which are so spaced on the bar as to cover the same distance as the ten type on the bar 58 do, and the bar is provided with eleven notches 53 to permit arresting the motion of the type bar with any of the type from one to eleven in printing position upon the line 45. The cyclical operation of the printing is not disturbed and the type bars 48 and 50 rise together to bring their type opposite the printing line. The type bar 48, however, may be controlled directly from an analyzing brush while the type bar 50 in order to compensate for its contracted type spacing must be controlled through a translating device, the entering impulses being retimed and rearranged as just explained. The printing magnet 51 is controlled from the counter magnet 64 during listing operations (see Fig. 14). Whenever the magnet 64 is energized during a tabulating operation it effects closure of contacts 88 thereby completing a circuit through the printing magnet 51, the closure of this circuit being substantially simultaneous with the entering impulse through the counter magnet so that the same data may be entered into the adding units and printed.

At the end of a card group as previously stated, the tabulating mechanism ceases operation and a total may thereafter be taken either automatically or by the pressing of reset button R. It will be recalled that the translating mechanism is set up during one card cycle and the reading, as modified, entered into the accounting mechanism during the following card cycle. This is the reason that the upper instead of the lower analyzing brushes have been used to control the reading-in mechanism. The last card cycle of a group is followed in the present machine by a totaling cycle and if it were attempted to control the translating mechanism from the lower brushes the data from the last card of each group would remain in the translating mechanism over the total taking operation and would be entered into the accounting mechanisms during the first tabulating cycle of the following group. Controlling the entry from the upper brushes, however, the

data from the last card is entered into the translator when the last card is passing the upper brushes and is read out as the last card is passing the lower brushes during the last tabulating cycle of the group.

The total taking circuit through the printing magnet 51 extends through contacts 90 whose operation is clearer from Fig. 4. This figure shows total taking mechanism associated with the counters which is fully described in the copending application of Lake Serial No. 639,193 filed May 5, 1923. A gear 93 constantly meshes with the train 70 to rotate whenever the counter wheel 69 rotates. Fast to this gear 93 is a stepped cam 92 having steps equal in number to the characters that are to be printed, that is, if operating according to the tens system of progression, it would be provided with nine steps corresponding to the digits from one to nine while if operating according to the twelfths system of progression, it would be provided with eleven steps corresponding with the numbers from one to eleven. During the total taking operation the type bars move uniformly as before through printing position and synchronously with this movement a shaft 95 rocks. Fast to this shaft is a frame 96 on which is pivoted a contact finger 97 carrying a set screw 98 at its end cooperating with the steps of cam 92. The finger 98 is held by a spring 99 in the position shown in the drawings against the frame 96 and it is provided with an arcuate rear extension 100 which is energized during the total taking cycle from a brush 101 fixed on the machine frame and sliding on the arcuate surface of 100. The frame 96 carries a brush 102 which when the finger 97 is in normal position against the frame is just clear of the arcuate extension 100. The frame and finger rock downward as the type bars rise until the set screw 98 encounters one of the steps on cam 92 whereupon the movement of finger 97 is arrested and the continuing motion of frame 96 causes the brush 102 to engage the arcuate extension 100 and thus initiate an entering impulse for the printing magnet. The position of the cam 92 always corresponds to the number indicated by the adding wheel 69 and the impulse initiated is therefore differentially timed during the cycle according to the numbers standing on the accumulator so that the proper type is selected for printing.

The structural details of the translating mechanism are shown in Figs. 1, 6 and 7. In Fig. 1 a complete translating unit is shown consisting of one reading-in commutator 55 and two sets of reading-out commutators 56 and 57. These commutators together with their operating magnets 62 and 63 are mounted on a common base plate 105. The commutators are all geared together and to the gear 82 on shaft 83 (see also Fig. 3) so that as the counting and printing mechanism

performs two cycles, the commutators each make one revolution. The commutators 56 and 57 with their brush shifting and other operating mechanisms are identical and only 5 one set will be described. The construction of the reading-out commutators will be most clearly understood from Figs. 6 and 7 of which Fig. 7 shows the parts in normal position and Fig. 6 shows the shiftable brush 10 65 shifted to engage the adjacent row of contacts 66 (see also Fig. 2). The brush 65 of which there are two for each commutator although only one has been shown in Figs. 6 and 7, is mounted on a pivoted lever 108 15 urged by a spring 113 to the position shown in Fig. 6 but normally restrained in the position shown in Fig. 7 by a latching mechanism consisting of an upward extension 109 on the lever 108 and a downward extension 20 110 on the pivoted supporting structure of the armature 111 of shifting magnet 63. When the magnet 63 is deenergized the lever 108 is held in the position shown in Fig. 7 by the extension 110 overlying the extension 25 109. When the magnet is energized to attract its armature as shown in Fig. 6 the extension 110 moves off the extension 109 and permits the spring 113 to shift the lever 108 bringing the brush 65 into the position shown 30 in Fig. 6. The commutator 57 is cut away for substantially half its periphery and this cut away portion is opposite the brushes 65 during that card cycle in which shifting impulses through the magnet 63 occur. Referring 35 to Fig. 1 it will be noted that the cut away portions of the reading-in commutators 56 and 57 are displaced 180 degrees with respect to their shiftable brushes so that the brushes of one set of commutators may be 40 freely set up during one machine cycle while the brushes of the other are reading-out an entry. The brushes 65 either in their shifted or unshifted position ride in grooves 112 in the raised portion of the reading-out commutators. These grooves serve to insulate 45 the ends of the brushes from each other and the contacts 66 are placed at the bottom of them. Shortly after the brushes 65 leave the grooves 112 any of them which have been 50 shifted to take a reading are shifted back to the normal position in Fig. 7. A pivoted arm 115 is provided with a pin 116 which extends into the path of a cam 117 mounted on the face of the driving gear of the commutator. This cam encountering the pin 55 rocks the arm 115 whose end thereupon restores the lever 108 to normal position allowing the extension 110 on the supporting structure of armature 111 to again engage the 60 projection 109 on lever 108 and hold it in this normal position until the magnet 62 is again energized.

The invention thus far has been explained in connection with a device for adapting a 57 twelve point progressive system to a ten

point machine but it is obvious that it is equally well adapted to other systems. In Figs. 10 to 13 a translating mechanism is indicated for operating in accordance with an eight point progressive system for handling eights fractions. In this case the counter mechanism and the printing mechanism for handling eights moves synchronously with the usual tens mechanisms performing a complete cycle in increments of 70 eights. In this case if the usual card indicated at H' in Fig. 11 is utilized for indicating eights only seven index points from zero to seven will be utilized and it will be necessary to expand this portion of the analyzing cycle to cover a complete normal analyzing 75 cycle as indicated. Here the spacing of the entering impulses must be expanded instead of contracted. In Figs. 12 and 13 a normal type bar 48 bearing ten type is aligned with a type bar 51 bearing eight type from zero to seven covering the same space longitudinally of the bar as the ten type on bar 48. The type bars as before rise synchronously and the retiming of the entering impulses according to Fig. 11 serve to compensate the different spacing on the eights type bar. In the case of the accumulating mechanism the drive for the eights counter wheel must, of course, be adjusted to provide for increments 80 of eights instead of tenths.

The developments of the reading-in and reading-out commutators for the eights transformation is illustrated in Fig. 10. The reading-in commutator 55' is identical 100 with the reading-in commutator 55 except that the transverse rows of contacts corresponding to the index points 9, 8, 10 and 11 have been omitted leaving only the rows from one to seven corresponding to index 105 point positions in which perforations may be placed. The reading-out commutators 56' rotate as before in synchronism with the counter driving mechanism and the printing mechanism but as in this case entering impulses may occur only in seven different positions only seven rows of transverse contacts 65' are provided, these seven rows being evenly spaced within the same space that the eleven rows occupied on the twelfths reading-out commutators. Aside from this different spacing of the contacts on the reading-out commutators the operation of the machine is identical with that explained in connection with the twelfths system. An index 110 point on a controlling record in the column representing eights result in shifting of certain brushes 65' and the contacts 66' are arranged in transverse rows so that the entering impulses are retimed as required to cover the complete normal entering and analyzing cycle.

The invention has now been described in connection with several embodiments to illustrate generally its distinctive features. It is 115 120 125 130

to be understood, however, that these embodiments have been selected merely with a view to illustrating the utility of the device and are not to be construed in a limiting sense. The transpositions, that is the rearranging of the timing of the pulses resulting from index points, is of general application. If desired two spaces in the middle part of the card for example the index points 5 and 6 might be left blank and these index points displaced to the 11 and 12 positions and transposed back to their proper position for entry by the transposing mechanism. The invention has also been described specifically with respect to mathematical progressions but it is not limited to the use of numbers as the operation of the machine itself involves the progression necessary for the operation of the device which may be 10 applied to alphabetical or other characters. I intend to be limited only as indicated by the scope of the following claims:

1. An accounting machine including data entering mechanism having a normal entering cycle and data receiving mechanism controlled thereby in combination with means cooperating with said entering means to enter data extraneously of said normal entering cycle and means for respacing the extraneous entries to bring them within the normal entering cycle for entry into the data receiving mechanism.

2. An accounting machine including data entering mechanism having a normal entering cycle and data receiving mechanism controlled thereby in combination with means cooperating with said entering means to enter data extraneously of said normal entering cycle and means for respacing the normal and extraneous entries to bring them all within the normal entering cycle for entry into the data receiving mechanism.

3. A record controlled accounting machine including record analyzing means and entry receiving means controlled thereby according to index points on predetermined portions of controlling records, means cooperating with said analyzing means to receive entries from index points on portions of controlling records exclusive of said predetermined portions and means controlled thereby for emitting entries corresponding to said last named entries in modified form for entry into the entry receiving means.

5. 4. A record controlled accounting machine including record analyzing means for successively searching index point positions on a predetermined portion of a record and entry receiving means controlled by said analyzing means according to index points on the record and having an entering period coextensive with the analyzing period, means cooperating with the analyzing means to receive readings from index points located 60 extraneous of the predetermined portion of

the record and means controlled thereby for emitting readings corresponding to said last readings in modified form for entry into the entry receiving means during its entering period.

5. A record controlled accounting machine including analyzing means for successively searching differentially located index points on a predetermined portion of a record during a normal analyzing period and entry receiving means controlled by said analyzing means according to index points on the record and having an entering period coextensive with the analyzing period, means cooperating with said analyzing means to receive entries from index points located extraneous of the predetermined portion of the record and means for respacing all entering operations to bring them within the entering period.

6. A record controlled accounting machine including analyzing means for successively searching differentially located index points on a predetermined portion of a controlling record during a normal analyzing period and for searching additional index points extraneously of the normal analyzing period, entry receiving means having an entering period coextensive with the normal analyzing period and means controlled by the analyzing means for receiving entries according to index points and respacing them within the normal entering period for entry into the entry receiving means.

7. A record controlled accounting machine including analyzing means for successively searching differentially and progressively located index points on a predetermined portion of a controlling record during a normal analyzing period and for searching additional index points located extraneous of the predetermined portion of the record and arranged in non-progressive order, entry receiving means having an entering period coextensive with the normal analyzing period and means controlled by the analyzing means for receiving entries from the analyzing means and respacing and rearranging them in progressive order for entry into the entry receiving means during the entering period.

8. A record controlled accounting machine including analyzing means for successively searching index points of a single index point system on a record arranged in non-progressive order, means controlled by the analyzing means for receiving single index point readings from the records and rearranging them according to a progressive order and entry receiving means operating according to the progressive order to receive the readings in the rearranged progressive order.

9. A record controlled accounting machine including record analyzing means for successively searching index points evenly spaced on a record and entry receiving means controlled by the analyzing means according to the dif-

ferential locations of the index points on the record, said entry receiving means having increments of entering movement different from the index point spacing on the records and means for modifying the entering operations to conform to the increments of entering movement.

10. A record controlled accounting machine including record analyzing means for successively searching index points evenly spaced on a record and entry receiving means controlled by the analyzing means according to the differential locations of the index points on the record, said entry receiving means having increments of entering movement less than the spacing between adjacent index point positions on the record and means for contracting the spacing of entering operations over the index point spacing to conform to the increments of entering movement of the entry receiving means.

11. A tabulating machine including synchronously operable record analyzing means and entry receiving mechanism each adapted for operation according to a single index point system and having operating cycles of different duration and means cooperating with the record analyzing means to receive single index point readings from records during the analyzing cycle and respacing them for entry into the entry receiving means within its operating cycle.

12. A tabulating machine including record analyzing means for successively analyzing spaced index point positions of a single index point system on controlling records, data receiving means including an element progressively movable by increments to manifest the data corresponding to index points the increments of movement of the elements differing from the analyses of successive index point positions, and means including devices for receiving single index point readings from the analyzing means and devices for respacing the single index point readings according to the increments of movement of the element for entry into the data receiving means.

13. A tabulating machine including record analyzing means for successively analyzing evenly spaced index point positions on controlling records, data receiving means including an element progressively movable by increments to manifest data corresponding to index points, the increments of movement of the element being less than the relative movement between the analyzing means and a record to analyze successive index point positions and means for receiving readings from the analyzing means and respacing them to conform to the increments of movement of the element for entry into the data receiving means.

14. A tabulating machine including analyzing means for successively analyzing in-

dex point positions on a controlling record during an analyzing cycle and entry receiving means synchronously operable therewith and including an element progressively movable by increments to manifest the data represented by index points, said element having an operating cycle of different duration than the analyzing cycle and means for receiving the index point readings from the analyzing means and emitting corresponding modified readings for entry into the entry receiving means during its operating cycle.

15. A tabulating machine including analyzing means for successively analyzing index point positions on a controlling record during an analyzing cycle and entry receiving means synchronously operable therewith and including an element progressively movable by increments to manifest the data represented by index points, said element having an operating cycle of different duration than the analyzing cycle and means for receiving the index point readings from the analyzing means and emitting corresponding modified readings for entry into the entry receiving means during its operating cycle, said means including a rotatable commutator with brushes shiftable transversely thereof under control of the analyzing means.

16. A tabulating machine including analyzing means consisting of a brush for each record column for successively analyzing index point positions on a moving record during an analyzing cycle and entry receiving means including an element movable synchronously with the record and by progressive increments to manifest the data represented by index points said element having an operating cycle of different duration than the analyzing cycle and means intermediate the analyzing brush and the entry receiving means for receiving a reading from the analyzing brush and emitting corresponding modified readings and comprising a rotatable commutator for controlling the entry receiving means and brushes shiftable transversely of the commutator and provided with shifting magnets in circuit with the analyzing brush.

17. A cyclically operable tabulating machine including analyzing means for successively analyzing index point positions on a controlling record during an analyzing cycle and entry receiving means synchronously operable therewith and including an element progressively movable by increments to manifest the data represented by index points, said element having an operating cycle of different duration than the analyzing cycle, means for receiving readings from the analyzing means during one machine cycle and emitting corresponding modified readings for entry into the entry receiving means during its operating cycle in a subsequent machine cycle.

18. A cyclically operable tabulating machine including analyzing means for successively analyzing index point positions on a controlling record during an analyzing portion of each machine cycle and entry receiving means synchronously operable therewith and including an element progressively movable by increments to manifest the data represented by index points, said element having an operating cycle of different duration than the analyzing portion of the machine cycle, means for receiving readings from the analyzing means during one machine cycle and emitting corresponding modified readings for entry into the entry receiving means during its operating cycle in a subsequent machine cycle coincidental with receiving a subsequent reading from the analyzing means.

19. A tabulating machine including record analyzing means and entry receiving means operating normally according to a decimal system of progression and means intermediate the analyzing and entry receiving means having devices for receiving entries from the records and devices for emitting corresponding modified readings to permit entries into the entry receiving means according to fractions having denominators other than ten.

In testimony whereof I hereto affix my
30 signature.

JAMES W. BRYCE.
